ATTORNEY

UNITED STATES PATENT OFFICE

BENJAMIN NEFF BROUNER, OF TAKOMA PARK, MARYLAND

ELECTRIC WIRE CONDUIT

Application filed November 31, 1930. Serial No. 497,283.

This invention relates to surface conduits for protectively carrying electric wires, and the like, over the floors of buildings, such conduits being used where it is undesirable 5 to cut into, or through the floors. Conduits of this character ordinarily present an unsightly and abruptly raised obstruction, which is liable to be torn loose from its position when accidentally kicked by persons 10 passing over it, and which, further, may sometimes cause serious falls to the persons so accidentally kicking or stumbling over the same.

Therefore, the object of this invention is 15 to provide a surface conduit, for application to a floor, which will obviate the above named, and other, objectionable features. Other objects may later become apparent.

In general, the conduit embodied by this 20 invention is characterized by a top wall, so constructed and arranged as to smoothly, and progressively, increase in height from each edge toward its central position. This construction presents a surface over which a person's foot may easily glide without interference, there being no surface against which the person's shoe may gain sufficient purchase to cause injury, either to the conduit, or to the person himself. The invention is 25 further characterized by a plurality of parallel walls, which extend longitudinally beneath the top along its length, so as to provide a passage, or passages, through which various types of electrical wires may be safely 30 conducted.

In the drawing:

Fig. 1 is an example of a surface conduit constructed in accordance with this invention.

Fig. 2 is another form, which may be used where it is not necessary to provide a completely enclosing conduit.

Figs. 3 and 4, respectively, are end and bottom plan views of a modified form, which is desirable because it may be constructed without, necessarily, the use of special dies.

Figs. 5 and 6 are, respectively, end and bottom plan views of another form of that shown 50 by the just preceding two figures.

Fig. 7 is an upstanding section permitting upward extension of a conduit.

Fig. 8 shows a T section, for use when one conduit must end in another.

Fig. 9 shows a union, or coupling, which 55 may be interposed between slightly separated ends of two sections to provide a safe exit for wiring carried therein.

Fig. 10 is a union, having a similar purpose to the one shown in Fig. 9, but adapted for 60 right angularly related conduits.

Fig. 11 is a cross section on the line 11—11 of Fig. 1.

In the drawing, similar numerals refer to 65 similar parts throughout the several views.

In Fig. 1 of the drawing, there is shown a conduit, formed integrally from sheet material, and consisting of a pair of upstanding vertical walls 12, the material being bent outwardly at the base or bottom of these walls 70 to form a pair of horizontal bottom walls 13. One of the walls 12 is doubled upon itself, down on its side facing the other wall, and then bent toward this other wall to provide a third bottom wall 14. Between each outer, and free, edge of the walls 13 the material is arched over to provide a top 15. This top, because of its shape, smoothly and progressively increases in height from each of its edges towards its central part, and is of a size 75 permitting its inner face to contact with, and be supported by, the upper edges of the walls 12. In order to fasten the conduit to a floor, the bottom walls 13 are provided with apertures 16, which are preferably downwardly 80 beveled to permit the application of countersunk screws 17, thus providing a firm, but non-obstructionable, fastening means. In order that the screws 17 may be inserted into the apertures 16, the top 15 is provided with holes 18 of sufficient size to permit application of the screws 17 therethrough, and the use of a screw-driver to drive the screws. If 85

nails are found desirable they may be positioned through the holes 18, and driven down to the bottom walls 13 by means of a nail set punch.

In some cases, it may not be necessary to provide a completely enclosing conduit. In such an instance, it is advantageous to employ 100

the form shown by Fig. 2 of the drawing, this being a modification of the just previously described form, and which eliminates the central bottom wall 14. This results in a considerable saving of material, and aids in the ease of installation of the wiring, it not being necessary to thread the wires through the central compartment. This figure also shows the holes 18, in the top 15, the same size as the 10 apertures 16, the screws or nails being passed through these holes so that the heads engage the top, and thus fasten the conduit to the floor. This arrangement places an obstruction in the two outer compartments, but these 15 compartments may, notwithstanding, be utilized to conduct electric wires of low voltages, such as buzzer wires, and the like, which require little room because of their less bulky insulating cover. This form of fastening 20 may, if desired, be substituted for the one previously described.

When a comparatively small footage of conduit is desired, the form of the invention shown in Figs. 3 to 6 may be more economically produced, in some instances, than that 25 shown by Figs. 1 and 2. Here the invention is shown with a top 19, of the identical shape of the top 15, but supported by a channel section 20. This channel section 20 is fixed to the 30 top 19 by soldering, spot welding, or the like, and may either have its closed face in connection therewith, or, if found preferable, the three edges of its sides. The first named form provides an open conduit, with its advantages 35 of easy installation, while the second form provides a closed conduit, which may be in some instances more desirable than the open conduit.

The section shown in Fig. 7 is for the purpose of extending a conduit up a wall or a 40 desk side. Fig. 8 shows a T section provided with an outlet hole 21 closed by a flush fitting plug 22. This hole is threaded, so that by removing the plug 22 a conventional electric wire bushing may be screwed therein to provide a safe wire outlet. The side walls 12 are preferably rounded where they form the mid-section, as shown by dotted lines, to form a non-abrasive corner against which the wires 45 may bear. This further provides a relative large space within the section, to permit the wires being spliced and wrapped with insulating tape in the usual manner.

It may sometimes be desirable to provide 50 an outlet for the conduits when they are laid in a straight line. The coupling shown in Fig. 9 will adequately accomplish this, two conduits being slightly separated from each other, and this coupling secured there-over to cover the space between them. It has an opening 21 of the identical form to the one previously shown, through which the conducted wiring may be passed. As this coupling is short in length, and will have each of its end edges supported by the sec-

tions of conduit on which it rests, there is no necessity for any internal bracing. The coupling shown by Fig. 10 has the same features, and is of the same construction as the one just described, with the exception 70 that it is of a right angle shape to accommodate right angularly disposed sections of conduit.

It will be seen from the foregoing that a 75 conduit constructed in accordance with this invention may be advantageously applied to a floor over which people constantly walk. When struck by one of their feet no damage will result, as the wedge-like action of its sides will cause the shoe to glide smoothly 80 over its top so as not to cause discomfort by stumbling. Neither is there any chance of it being torn loose or uprooted, for it is impossible to obtain sufficient purchase to apply any great force to it. It is inconspicuous even when laid upon an otherwise flat 85 floor, and may, because of its novel construction, be made extremely flat, and of little height.

Although various specific forms of the 90 invention have been shown, it is to be understood that one skilled in the art may conceive other forms not here shown, and it is intended that the appended claims cover the invention so as to apply to variations thereof.

Having thus described my invention, what I claim as new and desire to secure by Letters Patent of the United States is:

1. A surface conduit; comprising a plurality of spaced walls; base members having apertures extending out from the bottom edges of said walls; and a top, with its edges in connection with the free edges of said base members, and passing over the upper edges of said walls, said top being arcuate shaped from edge to edge and being formed with holes of a proper size and arranged so that fastening means may be completely passed therethrough for cooperation with the apertures of said bases to fasten the conduit to a surface.

2. A surface conduit formed of relatively thin material comprising an arcuate top portion arranged with its longitudinal edges contacting with a supporting surface when secured thereto, said portion having its outer face strictly following the curvature of an arc so as to be entirely free of angles and flat regions and with the radius of said arc and the transverse dimension of the top portion being such that the highest point of said outer face will lie close to said surface, and means located beneath said top portion for housing electric wires.

3. A surface conduit formed of relatively thin material comprising an arcuate top portion arranged with its longitudinal edges contacting with a supporting surface when secured thereto, said portion having its outer 120

face strictly following the curvature of an arc so as to be entirely free of angles and flat regions and with the radius of said arc and the transverse dimension of the top portion being such that the highest point of said outer face will lie close to said surface, and means located beneath said top portion for housing electric wires and for bracing and supporting the top portion between said longitudinal edges, said means comprising wall portions arranged relative to each other so as to extend across the conduit from edge to edge of the top portion and with at least one of said wall portions extending between said supporting surface and said top portion.

4. A surface conduit comprising a pair of parallel spaced walls, a wall extending laterally outwardly from an edge of each of said parallel walls, a top wall extending from the outer edge of one of said last mentioned walls to the outer edge of the other of said last mentioned walls, said top wall being arcuately shaped throughout its entire width so as to be entirely free of angles and flat regions, and an additional wall extending between said parallel walls.

In testimony whereof I affix my signature.
BENJAMIN NEFF BROUNER.
